UNITED STATES PATENT OFFICE.

FRANK CARTER AND EVERSHED CARTER, OF STAMFORD, ENGLAND, ASSIGNEES OF
ONE-THIRD TO GEORGE MILLS BLACKSTONE, OF STAMFORD, ENGLAND.

MEANS FOR IGNITING THE CHARGE IN INTERNAL-COMBUSTION ENGINES.

1,345,999.

Specification of Letters Patent.

Patented July 6, 1920.

Application filed March 26, 1919. Serial No. 285,312.

To all whom it may concern:

Be it known that we, FRANK CARTER and EVERSHED CARTER, both subjects of the King of Great Britain, and residents of Stamford, in the county of Lincoln, England, have invented a new and useful Improved Means for Igniting the Charge in Internal-Combustion Engines, of which the following is a specification.

10 This invention relates to engines of the kind described in specification of Patent No. 942,886 in which crude oil or other heavy fuel is injected or sprayed into the combustion chamber at or near the end of the compression strokes, by means of compressed air, and has for its object the provision of improved means for igniting such fuels, which constitute the main charge, without the use of high compression, or of

15 heated bulbs.

According to our invention we provide the combustion chamber with a port or passage in which is fitted a fuel and air mixing and ignition block furnished with a fuel spray, circulating ports and an electric igniter, such block being similar in construction to that described in the specification of Patent No. 1,171,018.

20 The fuel spray in this block is supplied with a suitable fuel, *e. g.*, paraffin or kerosene, although in some cases a heavier fuel such as tar oil may be used, and the port or passage above mentioned is so arranged that a flame issuing from it impinges upon the atomized jet of fuel injected into the combustion chamber through the main spray in the usual and well known manner. The injecting air for the igniting and main fuel sprays may be controlled by separate engine actuated valves, or by a single engine actuated valve. In the latter case the main fuel spray is provided with a valve, closed by a spring pressed piston and opened by the injecting air pressure acting against the

25 spring, in order to cause the main fuel spray to be slightly later than the igniting fuel spray which is controlled solely by the engine actuated valve.

The port or passage into which the block above mentioned fits, may be enlarged between the combustion chamber and the block to form an auxiliary combustion chamber in which the combustion of the igniting fuel charge occurs.

In the accompanying drawings:

Figure 1 is an end elevation of parts of an internal combustion engine, showing our invention.

Fig. 2 is a sectional plan of a portion of the combustion chamber taken on lines 1—1, 60 1—1, Fig. 1.

Fig. 3 is a vertical section on line 2—2, Figs. 1 and 2.

Fig. 4 is a vertical section on an enlarged scale taken on the line 3—3, Fig. 2.

Fig. 5 is a vertical section on an enlarged scale taken on the line 4—4, Fig. 1.

a is the combustion chamber and *b* the valve for admitting compressed air to the sprays. This valve is actuated by the cam 70 *c*, Fig. 1, through the bell crank lever *c'*, rod *c*², lever *c*³, spindle *c*⁴, and the forked lever *c*⁵, Fig. 4.

d is the compressed air supply pipe leading by way of the port *d*', Fig. 4, to the annular chamber *d*² and ports *d*³, *d*³ to the back of the valve *b*.

*d*⁴ is a port leading the compressed to the annular chamber *e*', Fig. 3, at the back of the fuel valve *f*, and *g*, *g*' are a pipe and a 80 passage respectively, supplying heavy fuel to said chamber *e*'. The valve *f* is provided with a piston *f*' and is pressed on to its seat by the spiral spring *f*².

*d*⁵, Fig. 4, is a port leading the compressed 85 air to the nozzle *h*', Fig. 5, in the ignition block *h*, in front of which the igniting fuel is conveyed by the pipe *i*, annular port *i*' and ports *i*², *i*². *j* is the igniting fuel and air mixing port, and *j*', *j*' are air circulating 90 ports operating as described in specification 1,171,018.

k, Fig. 5, is the insulated terminal, and *k*' the interrupter arm, actuated by the lever *l*, Fig. 1, and rod *l*' from the trip arm *m*' 95 of the magneto *m*. *n*, Fig. 1, is a crank pin by means of which the magneto lever *n*' is operated through the rod *n*².

o is a trip catch carried on the lever *n*' and adapted to be thrown out of engagement with the arm *m*' by the set pin *m*² catching the tail piece *m*³ when the lever *n*' is near the end of its outward stroke.

*m*⁴ is a stop to prevent the trip catch falling back too far to reengage the arm *m*'. 100

q, Fig. 2, is an auxiliary chamber into which the igniting fuel is sprayed and ignited, and *q*' is a port leading therefrom.

into the combustion chamber to direct the resultant flame on to the main fuel spray.

What we claim is:—

1. In an internal combustion engine of the kind in which a main fuel charge is injected into the combustion chamber near the end of the compression stroke, the combination of a sprayer for injecting the main charge, a spring-pressed piston f' provided in said sprayer, means for igniting said main fuel charge said means comprising a fuel and air mixing block (h) , a spraying nozzle (h') , a mixing port (j) , air circulating ports (j') in the block (h) , a communication passage leading from the block (h) to the combustion chamber, electrical means for igniting the charge sprayed by the nozzle (h') , and a single compressed air valve such as (b) to control both the main spray and the ignition spray.
2. In an internal combustion engine of

the kind in which a main fuel charge is injected into the combustion chamber near the end of the compression stroke, the combination of a sprayer for injecting the main charge, means for igniting said main fuel charge said means comprising a fuel and air mixing block (h) , a spraying nozzle (h') , a mixing port (j) , a communication passage leading from the block (h) to the combustion chamber, electrical means for igniting the charge sprayed by the nozzle (h') , a single compressed air valve such as (b) to control both the main spray and ignition spray, and the provision on the main fuel spraying valve of a spring pressed piston such as (f') .
